DRUM SUSPENSION

Ivar L. Langvand, Glen J. Schoessow, and Ernest A. Brooks, Barberton, Ohio, assignors to The Babcock & Wilcox Company, Rockleigh, N. J., a corporation of New Jersey

Application December 14, 1946, Serial No. 716,270

5 Claims. (Cl. 122—510)

The invention herein disclosed relates to the suspension of a pressure vessel subject to thermal expansion during operation, a more specific application of the invention being to the suspension of a horizontally disposed cylindrical drum associated with a boiler or other heat transfer apparatus.

Heretofore, in the suspension of a boiler drum from an overhead stationary structure, it has been customary to employ a pair of drum straps in the form of U-bolts engaging the lower half of the drum adjacent opposite ends, each U-bolt being formed of a continuous length of steel rod of circular cross-section and being supported by its threaded upper ends on washer members designed to permit limited angular movement of the strap in accordance with the longitudinal drum movement caused by temperature changes. For boilers of small and medium capacities such a means of support has been found entirely satisfactory.

In large capacity boiler units, the major portion of the weight is supported from the top and includes not only weight of the boiler structure but also weight of the furnace structure. In such units, certain parts associated with either the boiler or furnace structure, or both, are connected to the drum and are supported thereby, so that supports for the drum must sustain a total weight in excess of the weight of the drum itself. The total drum load to be suspended also increases with the pressure at which the boiler is designed to be operated due to the greater wall thicknesses required for the drum and associated suspended pressure parts. It follows therefore that as a primary requirement the drum suspension members must have relatively large cross-sectional areas to provide adequate tensile strength for support of the total drum load involved.

In modern central station boilers of increasingly higher capacities and pressures, the main steam and water drums may have diameters ranging upwardly to about 6 feet and lengths upwardly of 40 feet, involving drum loads ranging, for example, between 1,000,000 and 2,000,000 pounds. In the usual boiler construction an upper boiler drum can be supported only adjacent its ends exteriorly opposite upright walls of the setting, thereby determining the areas of support or suspension at widely separated locations, such as 40 feet or more apart measured longitudinally of the drum. When the boiler is placed in operation and the drum brought up to saturation temperature, thermal elongation of the drum causes the two drum support areas to become more widely separated and the lower ends of the suspension members to be moved apart a corresponding distance, in some instances the drum elongation being about two inches, with the drum engaging end of each member moving outwardly a distance of about one inch. Such movement of each suspension member adjacent the drum is, of course, greater at the higher operating pressures due to the higher saturation temperatures and must be provided for by deflection in the member itself, or by some special support arrangement, since the steel supporting structure to which the member is attached remains at a considerably lower temperature. Special support arrangements have been proposed whereby such movements of the suspension members are permitted without stress inducing deflections therein but such devices are of complicated construction and expensive due to the high bearing loads and high shearing forces involved.

When drum straps of the circular section U-bolt type are employed for large high pressure drums and corre-

2

spondingly heavy drum loads, the requirements involve a steel rod of large cross-section to withstand the direct tension load involved, and a rod also of sufficient length to permit the necessary amount of deflection due to drum elongation without exceeding a predetermined maximum total working stress of 15,000 p. s. i., for example, inclusive of direct tension and bending stresses, the rod being considered as a cantilever fixed at the drum and free at its upper rocker-supported ends. Solid steel rods of large diameters may lack the required uniformity of metallurgical quality. The use of large circular section rods may also involve lengths which are considerably greater than the height available or desired between the drum and the overhead drum supporting structure. Limitation of drum strap length is therefore an important consideration in its effect on overall boiler height for any given boiler construction.

An object of our invention therefore contemplates an improved form of drum suspension permitting the drum to be positioned closely adjacent its overhead stationary support and thereby in boiler construction contributing to a reduction in overall boiler height.

Another object of the invention is to provide a drum suspension in which the total load is divided between elements of relatively small cross-section adjacent each end of the drum.

An additional object is to provide drum suspension elements of predetermined uniformly high quality throughout their cross-section.

30 A further object is to provide a drum suspension unit comprising a group of suspension elements of which each has its minimum moment of inertia about an axis normal to longitudinal movement of the drum.

A more specific object is to provide a multiple plate suspension unit of generally U-shaped formation in which sliding and friction between plates is maintained at a minimum.

The various features of novelty which characterize our invention are pointed out with particularity in the claims 40 annexed to and forming a part of this specification. For a better understanding of the invention, its operating advantages and specific objects attained by its use, reference should be had to the accompanying drawings and descriptive matter in which we have illustrated and described 45 a preferred embodiment of our invention.

Of the drawings:

Fig. 1 is an elevational view featuring an improved form of drum strap as an embodiment of our invention;

Fig. 2 is a side view of the structure illustrated in Fig. 50 1; and,

Figs. 3, 4 and 5 are enlarged vertical sections of Fig. 1 taken along lines 3—3, 4—4, and 5—5, respectively.

Figs. 1 and 2 illustrate an embodiment of our invention as applied for example to the suspension of a cylindrical steam and water drum 12 which for the purpose of this application may be taken as the principal supported element in a high capacity high pressure vapor generating unit of the construction disclosed in the copending application of Arthur E. Raynor, Serial No. 638,941, filed January 4, 1946, and since issued as U. S. Patent 2,512,677, dated June 27, 1950. The drum 12 is suspended by means of drum straps 14, of which one only is shown, from an overhead supporting frame structure which includes horizontally extending beam members 16 and 18 having their upper flange surfaces in a common horizontal plane 19, the two drum straps 14 engaging the drum 12 adjacent opposite ends at locations exteriorly of opposite side walls of the boiler setting as indicated more particularly in the aforesaid application, the outer surface of one such wall 70 being indicated by line 21 in Fig. 2 of the present application, the adjacent drum end thus being toward the left of wall 21 as viewed in this figure.

Each drum strap 14 is of multiple plate construction providing a suspension unit of generally U-shaped formation, as seen in Fig. 1, the lower loop portion or drum saddle section 23 of the strap embracing substantially the entire lower half of drum 12, and the upright leg portions or sections 24 extending upwardly to an elevation above the short length I-beam members 25 which are secured by welds 26 to the horizontally spaced I-beam members 16 and 18, or other adjacent portions of the

main supporting frame, each I-beam member 25 being reinforced by plates 27 which are secured thereto by welds 28. Each leg of strap 14 terminates in a transverse upper end portion or section 29 by which drum load is transferred through I-beam members 25 to the main supporting structure, each terminal portion 29 being seated on wedges 31 inserted between portion 29 and the beam members 25 for the purpose of adjustment as hereinafter described, and the wedges maintained in final position relative to supports 25, for example, by welds 32.

The lower loop portion 23 of each strap 14 comprises a group of horizontally spaced arcuately formed saddle plates 34 arranged in edgewise relation with respect to drum 12 and assembled with filler plates or spacers 35 therebetween which are secured to adjacent plates 34 by welds 36, the inner arcuate edge of each plate 34 having recesses or relieved areas 37 therein at intervals to provide arcuately spaced drum engaging portions 38 which when the plates 34 are assembled are machined to the measured radius of the outer wall of the drum, the provision of recesses 37 resulting in a closer proximity of fit with the drum and a more uniform loading of each saddle plate 34. The plates 34 terminate in horizontal upper edges 39 at substantially the level of the horizontal central axis of drum 12.

The vertically disposed leg portion 24 of each strap 14 comprises a group of relatively narrow flat hanger bars or plates 41 of rectangular cross-section interleaved in pairs at their lower ends with the spaced upper ends of saddle plates 34 to which plates 41 are connected by two rows of round bars or pins 42 having threaded ends to receive the holding nuts 43 which are suitably tacked welded thereto, a rectangular washer 45 being inserted between each nut 43 and an outer saddle plate 34. The spacing of the pairs of hanger plates 41 in each leg of the strap is maintained by means of pipe spacers 46, at one or more elevations, through which bolts 47 are inserted and the entire group of plates 41 tied together against the spacers by means of nuts 48, a washer 49 being suitably inserted between each bolt head and nut and the adjacent outer plate 41. The plates 41 are thus maintained at substantially equal spacings throughout their lengths and, due to clearances provided around bolts 47 through the plates and pipe spacers, provide a unitary structure having high tension load characteristics without unduly increasing the resistance of the assembly to deflection, each plate 41 being free to move relative to an adjacent plate to a limited extent and thereby functioning more nearly as an individual plate, in so far as deflection is concerned, than if incorporated in a totally rigid assembly. Each plate 41, in cross-section, is of smaller dimension longitudinally of the drum than in a direction normal thereto, thereby providing its minimum moment of inertia about an axis normal to the plane of its deflection, that is, a vertical plane parallel to the longitudinal axis of the drum.

The transverse upper end section or cross piece 29 in which each drum strap 14 terminates comprises spaced plates 51 interleaved with the upper ends of the hereinbefore mentioned pairs of hanger plates 41, each set of cross piece plates 51 and hanger plates 41 being held together in assembled pivotal relation by a pin 52 having threaded ends to receive the holding nuts 53 which are suitably tack welded thereto, a rectangular washer 54 being inserted between each nut 53 and the adjacent outer cross piece plate 51. In the form shown, where three pairs of plates 41 are employed in each leg 24 of the strap, the plates forming the central pair terminate above the cross piece 29 in an upwardly extending portion 56 having a hole 57 therein mainly for purposes of erection, whereby a strap 29 may be lifted into and held in position prior to and during assembly of the cross piece plates 51, and during adjustment and welding of wedges 31, there being a separate pair of oppositely inclined wedges 31 cooperating with the inclined lower edges 58 of each cross plate 51 so as to afford independent adjustment of each such plate whereby accurate alignment of the holes in plates 41 and 51 may be attained for the reception of pins 52, and vertical adjustment of drum position effected, the plates 51 thereafter being maintained in alignment by means of bars 59 extending across opposite ends of each group of plates 51 and each welded to all plates of a group.

In the construction of drum strap described, full advantage is taken of the elastic properties of the metal of which the plates are formed. In addition to the loading of the strap plates 41 in direct tension, there is a bending stress to be accommodated as a result of the deflections accompanying variations in drum length in response to temperature changes. However, the hanger plates 41 are relatively thin in the direction of drum movement and thus are capable of being deflected to the extent required without causing any considerable increase in total working stress due to bending, each plate having for example a thickness of three-eights to three-quarters of an inch and a width of approximately twenty to thirty times the thickness. The total working stress, inclusive of stresses in direct tension and bending, is therefore maintained well within permissible limits for the metal involved. The small addition of stress due to bending enables shorter straps to be employed so that a considerable reduction in height of the supporting steel structure may be effected and a more economical boiler installation provided. Apart from an economical standpoint, there are occasions when a limited available height is a controlling factor in the design of boiler that can be installed in which cases employment of the present disclosed form of suspension is especially beneficial.

The provision of a laminated structure as shown, utilizing a plurality of plates throughout, is also advantageous in that at each connection between sections the total shearing force is subdivided and thus applied in correspondingly smaller units at a greater number of locations, thereby permitting the use of connecting pins of relatively small cross sectional areas. The pins of reduced cross section are also suitable as regards resistance to bending because of the plurality of points of support and the resulting short span between these points of support. In the connection between the saddle plate section 23 and each upright leg section 24, where a plurality of pins 42 are utilized, the shearing forces are further distributed and the required cross sectional area of each pin correspondingly reduced.

In addition to the deflection of strap plates 41 in the direction of drum movement there is also a certain amount of radial movement which takes place due to radial expansion of the saddle plates 34 so that the resultant movement of the strap plates deviates slightly from normal with respect to the plane of the plates and ends to produce a slight twist in the plates. However, this radial component of plate movement is relatively small considering the extent of axial movement involved. Any increase in bending stress due to the twist is thus maintained at a low value and is no detriment to operation for the extent of drum length variations normally encountered.

While in accordance with the provisions of the statutes we have illustrated and described herein the best form of our invention now known to us, those skilled in the art will understand that changes may be made in the form of the apparatus disclosed without departing from the spirit of the invention covered by our claims, and that certain features of our invention may sometimes be used to advantage without a corresponding use of other features.

We claim:

1. In heat transfer apparatus, a horizontally axised cylindrical drum subject to variations in its axial length as a result of thermal expansion and contraction, a suspension for said drum comprising a drum supporting saddle section embracing the lowermost surface portion of said drum, a pair of upright hanger sections having lower end portions rigidly connected to transversely spaced portions of said saddle section, and means pivotally connected to upper end portions of each of said hanger sections for transferring suspended drum weight to an overhead load supporting structure, said saddle section and said hanger sections each comprising longitudinally spaced plates interleaved with and connected to plates of the respective other sections, each of said plates of said hanger sections having its upright facing surfaces substantially normal to the longitudinal axis of said drum, each of said saddle plates presenting a concave upper edge portion toward said drum and providing therewith mutually contacting surfaces of substantially common curvature about the longitudinal axis of said drum, one of said last named surfaces being formed with arcuately spaced recesses therein to reduce the area of saddle plate engagement with said drum.

2. Apparatus for suspending a horizontally elongated drum comprising a rigidly formed drum saddle section adapted to extend transversely of said drum to positions at opposite sides of said drum, a pair of vertically disposed hanger plate sections arranged substantially in a common plane at opposite ends of said saddle section and each adapted to flex in a direction normal to said plane, means rigidly connecting the lower ends of each of said hanger plate sections to said opposite ends of said saddle section, and means pivotally connected to upper ends of each of said hanger plate sections for transferring suspended weight to a load supporting structure, said hanger plate sections respectively comprising a plurality of plates each of substantially lesser thickness than width in directions respectively transverse and parallel to said plane.

3. Apparatus for suspending a horizontally axised cylindrical drum which during operation is subject to thermal expansion, said apparatus comprising a rigidly formed drum saddle section having an arcuately formed upper surface portion adapted to engage a similarly formed lower surface portion of said drum, a pair of vertically extending flexible hanger sections arranged in horizontally spaced relation throughout and having lower end portions rigidly connected longitudinally of said drum to horizontally separated portions of said saddle section, and means separately connected in pivotal relation to upper end portions of each of said hanger sections for transferring suspended drum weight to a load supporting structure, each of said hanger sections being formed of relatively thin plates of substantially lesser thickness than width in directions respectively parallel and transverse to the longitudinal axis of the drum to be supported and of substantially greater vertical length than the horizontal distance separating said hanger sections.

4. Apparatus for suspending a cylindrical drum which has its longitudinal axis horizontally disposed and which during operation is subject to variations in length as a result of thermal expansion, said apparatus comprising a saddle section of rigid formation having a concave upper drum seat portion adapted to engage a lower arcuate portion of the drum to be suspended, a pair of upright hanger

sections arranged in horizontally spaced relation throughout in a direction transverse to said axis, means rigidly connecting longitudinally of said drum the lower end portions of said hanger sections to horizontally opposite upper end portions of said saddle section, and means pivotally connected to upper end portions of said hanger sections for transferring suspended drum weight to a stationary support, each of said hanger sections being formed of relatively thin plates arranged transversely of said axis and extending vertically in lengths substantially greater than the horizontal distance separating said hanger sections so as to render said plates flexible in the direction of said drum length variations, said plates of each of said hanger sections being arranged in groups spaced apart in a direction parallel to said axis and interconnected at intervals throughout the height of said hanger sections.

5. Drum suspension apparatus as claimed in claim 4 wherein individual hanger section plates have an average width dimension transversely of said axis of the order of 20 at least twenty times an average thickness dimension longitudinally of said axis so as to resist flexing in a direction transverse to the length of the drum.
